Patented Nov. 11, 1913.

UNITED STATES PATENT OFFICE.

FREDRICK W. BAXENDALE, OF STREATOR, ILLINOIS, ASSIGNOR OF ONE-HALF TO
WALTER E. BAXENDALE, OF STREATOR, ILLINOIS.

WEATHER-STRIP.

1,078,531.

Specification of Letters Patent.

Patented Nov. 11, 1913.

Application filed June 26, 1912. Serial No. 706,099.

To all whom it may concern:

Be it known that I, FREDRICK W. BAXENDALE, a citizen of the United States, residing at Streator, in the county of La Salle, State of Illinois, have invented certain new and useful Improvements in Weather-Strips; and I do hereby declare the following to be a full, clear, and exact description of the invention, such as will enable others skilled in the art to which it appertains to make and use the same.

The invention relates to weather strips and particularly to that type adapted for use in connection with a swinging door to close the space between the threshold and the lower edge of the door so as to exclude wind, moisture and dust.

The object of the invention resides in the provision of a weather strip of the character referred to which may be readily attached to any door without the necessity of applying unsightly strips and which may be adjusted so as to conform in its operation to spaces of various width between different doors and respective thresholds.

A further object of the invention resides in the provision of a weather strip which will be simple in construction, efficient in use, and comparatively inexpensive to install.

With the above and other objects in view, the invention consists in the details of construction and in the arrangement and combination of parts to be hereinafter more fully described and particularly pointed out in the appended claim.

In describing the invention in detail, reference will be had to the accompanying drawings wherein like characters of reference denote corresponding parts in the several views, and in which—

Figure 1 is a side elevation of the lower portion of the door showing the invention applied, a portion of said door being broken away to disclose the relative location and disposition of the component parts of the invention, Fig. 2, a view similar to Fig. 1 with the door in open position, Fig. 3, a section on the line 3—3 of Fig. 1, Fig. 4, a front elevation of the device detached from the door, Fig. 5, a plan view of what is shown in Fig. 4, and, Fig. 6, a rear elevation of the device.

Referring to the drawings 10 indicates a door and 11 the jamb thereof all of the usual

and well known construction. The lower edge of the door 10 is provided with a groove 12 for a purpose that will presently appear. The weather strip is shown as comprising a U-shaped plate A including spaced arms 13 and 14 and an arm connecting portion 15. The arm connecting portion 15 of the plate A is of less width than the arms 13 and 14 and one side edge of said arm connecting portion is disposed in registration with the corresponding side edges of the arms 13 and 14 while the other side edge of said arm connecting portion is disposed inwardly of the corresponding side edges of the arms 13 and 14, said last named side edge of the arm connecting portion being indicated at 16. The arms 13 and 14 are provided at their lower ends outwardly of the edge 16 of the arm connecting portion with inwardly directed ears 17 and 18 disposed in spaced relation to the edge 16 and having their outermost side edges in registration with the corresponding side edges of respective arms 13 and 14. Formed on the arm connecting portion 15 at the edge 16 thereof are spaced ears 19 and 20 which are bent upwardly at right angles to the arm connecting portion.

The arms 13 and 14 are provided with aligned openings 21 and 22 respectively in which is slidably mounted a bar 23. The end of the bar 23 slidable in the opening 21 is reduced to form a shoulder 24 and a bearing plate 25 is secured against the inner face of the arm 13. A spring 26 encircles the reduced end of the bar 23 and one end of this spring bears against the shoulder 24 while the other end thereof engages the bearing plate 25. The end of the bar 23 remote from the spring 26 is threaded as at 27 and engaged on this threaded end of the bar is a lock nut 28 and a sleeve 29. This sleeve 29 projects outwardly of the arm 14 and may be adjusted on the threads 27 so that a greater or less length of sleeve is disposed outwardly of the arm 14, the nut 28 serving to lock the sleeve against rotation on the threads 27 after said sleeve has been adjusted in a desired manner.

Pivoted on the ears 19 and 20 respectively are angle levers 30 and 31, corresponding ends of which latter are pivotally connected to the bar 23 so that the reciprocation of the latter will rock said angle levers. The other corresponding ends of the angle levers 30

and 31 are pivotally connected to ears 32 and 33 respectively formed on a strip 34, which latter is movable between the ears 17 and 18 and the edge 16. By this construction it will be apparent that when the bar 23 is moved longitudinally against the influence of the spring 26 said strip 34 will be moved outwardly with respect to the arm connecting portion 15 of the plate A while the opposite movement of the bar 23 will cause said strip 34 to be drawn inwardly of the arm connecting portion 15. The lower edge of the strip 34 is provided with a layer of rubber 35 so as to assure a weather tight joint between the strip 34 and the threshold of the door when said strip is moved outwardly of the arm connecting portion 15 into engagement with the threshold.

In applying the device to the door 10 the lower end of the door is emaraced by the plate A and the arms 13 and 14 countersunk in and secured to respective side edges of the door, the groove 12 serving to receive the bar 23, angle levers 30 and 31, strip 32 and ears 19 and 20. The end of the bar 23 which carries the sleeve 29 is disposed adjacent the hinged side of the door 10 so that the projecting portion of the sleeve 29 will engage a suitable plate 35' on the jamb 11 as the door is closed and result in the bar 23 being moved against the influence of the spring 26 so as to force the layer of rubber 35 into engagement with the threshold. As the door is opened the spring 26 will auto-

matically move the bar 23 to draw the strip 34 and layer of rubber 35 inwardly of the arm connecting portion 15 in the manner previously referred to. By adjusting the sleeve 29 on the bar 23 it will be apparent that greater or less movement may be imparted to the strip 34 as the door is closed so as to render the device applicable irrespective of the distance of the lower edge of the door from the threshold.

What is claimed is:

As an article of manufacture, a weather strip comprising a U-shaped body plate, one side of the bight thereof being provided with pairs of slits and the portion between each pair being bent upwardly to provide lugs, a plate, the bight portion of the body plate being longitudinally slitted to receive the second plate, angle levers pivoted at their angle portions to the lugs and pivoted to the second plate a bar having reduced ends loosely passed through the arms of the body plate, the levers being pivoted also to said bar and an expansible spring disposed about one reduced end and bearing against the main end and against the arm of the plate.

In testimony whereof, I affix my signature, in presence of two witnesses.

FREDRICK W. BAXENDALE.

Witnesses:

J. J. THORPE,
P. H. DORAN.
